NICHOLAS MÜLLER, OF NEW YORK, N. Y.

Design No. 2,563, dated January 22, 1867.

DESIGN FOR A CLOCK CASE.

The Schedule referred to in these Letters Patent and making part of the same.

TO ALL WHOM IT MAY CONCERN:

Be it known that I, NICHOLAS MÜLLER, of the city, county, and State of New York, have invented a new and ornamental Design for Clock Case; and I do hereby declare that the following is a full, clear, and exact description thereof, which will enable those skilled in the art to make and use the same, reference being had to the accompanying drawing, forming a part of this specification, in which—

Figure 1 represents a front view of the design.

Figure 2 is a side elevation of the same.

Similar letters of reference in both views indicate corresponding parts.

This invention relates to a design for a clock case, the back ground of which represents a wall surmounted by an arch. The top of the arch is ornamented by a human head and its sides with arabesques. A butterfly embellishes one side of the wall, while the other side is partly covered by the branch of a shrub, under which and on the side of the case repose a mouse. In the middle and close down to the bottom of the case is a snail creeping upwards, and the sides are ornamented by bunches of grass growing out of the wall.

A represents the wall, which is surmounted by the arch, B. This arch is ornamented by a head, C, and arabesques, D. On one side of the wall, and below the arch, is a butterfly, E, whereas the other side of the wall is partly covered by the branch, F. Under this branch and on the side of the wall repose the mouse, G, and on that portion of said branch nearest to the ground creeps a snail, H. Bunches, I, of grass grow out of the bottom part of the wall near its edges.

What I claim as new, and desire to secure by Letters Patent, is—

The design for a clock case as herein shown and described.

The above specification signed by me this 18th day of December, 1866.

NICHOLAS MÜLLER.

In presence of—

W. HAUFF,

RUDOLPH WUSTE.
